UNITED STATES PATENT OFFICE.

WILLIAM BRIDGES, OF DARBY, PENNSYLVANIA.

BUILDING BLOCK.

Application filed October 19, 1923. Serial No. 669,457.

To all whom it may concern:

Be it known that I, WILLIAM BRIDGES, a citizen of the United States, residing at Darby, in the county of Delaware and State 5 of Pennsylvania, have invented certain new and useful Improvements in Building Blocks, of which the following is a specification.

My invention relates to building blocks 10 and its objects are to provide a block which may be attached to any part of a building; may be made with any desired configuration on its face to imitate brick, tile, stucco, etc., and which may be easily attached.

15 These objects, and other advantageous ends which will be described hereinafter, I attain in the following manner, reference being had to the accompanying drawings in which—

20 Figure 1 is a face view of a building block constructed in accordance with my invention,

Figure 2 is a section on line 2—2 of Figure 1,

25 Figure 3 an end view of Figure 1, Figure 4 a fragmentary view of the studding of the building illustrating my blocks attached thereto,

30 Figure 5 an enlarged section on line 5—5 of Figure 4,

Figure 6 a fragmentary view similar to Figure 4 showing a modified shape of the cavity, and

35 Figure 7 a diagrammatic view illustrating various shapes that may be used in forming the outline of the cavity.

Referring to the drawings, 1 indicates a 40 block which is made of concrete or the like in the form of a thin rectangular body with

grooves 2 in its upper and lower edges. Cavities 3 are formed in face 4 of the block and lead to its side edges 5. The outlines 6 of the cavities are of V-shape and when the blocks are placed together, as on the building structure shown in Figure 4, will form 45 a diamond shaped cavity. However, the outlines of the cavities may be of any desired shape, several shapes being shown in Figures 6 and 7. A recess 7 is formed with

50 in each cavity 3 and leads out to the edge 5. A semi-circular groove 8 extends from the recess to the rear face of the block.

When the blocks are assembled to form a 55 wall, as shown in Figure 4, the edges 5 will meet and the cavities 3, recesses 7 and groove

8 of their meeting edges will coincide to form a diamond shaped cavity, a rectangular shaped recess and a circular opening as shown in Figures 4 and 5. A rectangular washer 9 is provided with an opening 10 60 which registers with grooves 8. A spike 12 passes through opening 10 and between grooves 8 into studding 11 of the supporting structure and holds the blocks thereto. A filler 13 covers the rectangular washer 9 65 and spike 12 and fills the cavity to produce a surface flush with the face 4 of the blocks. Face 4 may have configurations thereon which correspond with the diamond shaped cavity, shown in Figure 4 or which represent rectangular blocks such as bricks. Any shape of cavity may be used with any corresponding configuration on surface 4, so long as there is a cavity below surface 4 to receive a filler and a recess below the cavities into 70 which a washer of any shape may be inserted so that a spike or bolt may be passed through the washer and driven into the supporting structure.

75 Blocks constructed in accordance with my invention may be easily attached to any supporting structure by simply driving in spikes. The upper and lower edges of the adjacent blocks are anchored to each other by filling the groove 2 with mortar.

80 While I have described my invention as taking a particular form, it will be understood that the various parts may be changed without departing from the spirit thereof, and hence I do not limit myself to the precise construction set forth, but consider that 85 I am at liberty to make such changes and alterations as fairly come within the scope of the appended claims.

Having thus described my invention, what 90 I claim as new and desire to secure by Letters Patent is:—

95 1. A building block having a cavity in its face and a recess within the cavity, the cavity and recess leading to the edge of the block and being adapted to receive means for securing the block to a building and a filler to cover the securing means.

100 2. In combination with a supporting structure, building blocks having cavities and recesses within the cavities, the cavities and recesses in each block leading to the meeting edges and coinciding with the cavities and recesses of the adjacent blocks; a washer within the recesses; means passing 105

through the washer for securing the blocks to the structure, and a filler within the cavities for covering the washer.

3. In combination with spaced studding, building blocks abutting each other at their vertical edges adjacent the center of each studding, each block having a cavity and a recess in the cavity leading to the abutting edges and coinciding with a similar cavity and recess in the adjacent block; common means within the recesses for securing the abutting edges of the block to the studding, and a filler within the cavity for covering the securing means.
- 10 4. In combination with spaced studding, building blocks abutting each other at their vertical edges adjacent the center of each

studding, each block having a cavity and a recess in the cavity leading to the abutting edges and coinciding with a similar cavity and recess in the adjacent block; a washer in the recesses; means passing through the washer and between the edges for securing the blocks to the studding, and a filler in the cavity for covering the washer and securing means.

In testimony whereof I have signed my name to this specification in the presence of two subscribing witnesses.

WILLIAM BRIDGES.
